FIG. 2

FIG. 4

FIG. 3

FIG. 1

Inventor
William B. Philippe
By Cornwall, Bedell & Janus, ATTYS.

UNITED STATES PATENT OFFICE.

WILLIAM B. PHILIPPE, OF ST. LOUIS, MISSOURI.

OIL BURNER.

Application filed February 16, 1924. Serial No. 693,239.

My invention relates to oil burners of the gravity-feed type as applied to stoves and furnaces for heating purposes. The invention consists in an improved burner construction and in the positioning and assembly of the same with the heater in which it is installed.

The main object of my invention is to provide an air draft which will insure perfect combustion, thereby eliminating the deposit of soot upon the burner and heating surfaces. In attaining this object, it is desirable that the various parts of the burner should be adjustable relative to each other and, in some respects, adjustable while in operation, and other objects of my invention are the provision of means for securing such adjustment. It is also desirable that the air admitted to the burner be preheated and another object of my invention is to so heat the air.

In the accompanying drawings which illustrate a selected embodiment of my invention—

25 Figure 1 is a vertical section through a hot air furnace of ordinary type in which a burner including my invention is installed.

Figure 2 is a horizontal section through the furnace and includes a top view of my burner cut away in part for better illustration.

Figure 3 is in part a side elevation and in part a vertical section taken on line 3—3 of Figure 2.

35 Figure 4 is in part an end elevation and in part a vertical section taken on line 4—4 of Figure 3.

The burner comprises four chief members, a base 1, an oil receiving member 2, a conduit forming member 3, and a shell 4 forming an air passage adapted to secure maximum flow of air to the air conduits.

In operation, oil flows by gravity through supply line 5 to the saucer-shaped portion 6 of member 2 which is terraced as best indicated in Figure 4 and is provided with a series of grooves 7 which successively receive the oil overflowing saucer 6. The air which unites with the oil vapor to form a combustible gas enters the furnace A through the draft door B at the bottom of the furnace and passes without obstruction upwardly throughout the entire area of the grate C. The area of the air passage through the furnace fire-box is gradually reduced by deflector 4 until the air reaches base 1 where

it enters vertical conduits 8 which are connected with horizontal conduits 9 terminating in a downwardly directed discharge outlet 10 just over the terraced oil receiving member 2. The gradual decrease in diameter of the deflector and the elevation of the burner above the air inlet of the heater produce a flow of air through the conduits which cannot be obtained with an installation in which a horizontal plate or wall closes the space between the fire-box wall and the burner. The exterior of the deflecting shell 4 is exposed to the hot gases in the fire box of the furnace and this arrangement results in heating the air admitted to the burner.

It will be noted that the burner base 1 and the oil receiver 2 are oval in shape and that the air conduits 8 are positioned at the ends of the major axis of the oval and that the horizontal conduits 9 extend parallel with this axis.

By making the burner oval in contour, the distance between the oil receiving grooves 80 and conduits 9 is maintained at a minimum and the conduits are better heated than if a circular terrace was used.

The bottom of member 2 is preferably provided with horizontal flanges 12 in which are openings adapted to receive the shouldered ends of screws 13 which are threaded into base 1 and may be screwed in or out to raise or lower the adjacent portion of member 2. By means of these screws the entire member 85 2 may be raised and lowered from the base and what is more important the member may be leveled so that the oil flowing over the terraces will flow equally in all directions.

The base 1 is provided with upstanding collars 14 at each end over which slide the vertical conduits 8 of member 3. This telescoping assemblage of the conduits and base permit the conduit to be adjusted vertically relatively to the base and to member 2 95 by means of rods 15 which engage sockets 19 and extend downwardly through the base, deflector 4 and the grate bars C to any suitable elevating arrangement, here shown as bell cranks 16 each having one arm pivotally connected to one of the rods 15 and having the other arm connected to a horizontal rod 17 extending through the side of the furnace and adapted to be adjusted by means of a thumb screw 18 to raise or lower rods 100 15 and conduit member 3.

It will be noted that the furnace is pro-

vided with the usual draft door B and fire-door D spaced vertically a substantial distance from each other and that the oil burner is so located that its bottom is above the 5 bottom of the fire-door and is, therefore, a substantial distance above grate C. This arrangement not only permits the generation of a stronger draft through deflector 4 but also places the burner in a position where 10 its operation may be observed through the open fire-door without having the operation unduly affected by the opening of the door. It has been customary to place oil burners directly upon the grate bars or to elevate 15 them a slight distance above the same but in such installations as I am familiar with, it has been impossible to observe the operation of the burner since the opening of the fire-door would produce a draft of air from 20 the fire-door to the furnace chimney which was entirely above the burner and so reduce the burner flame that observation was use- 25 less.

With my construction there is a sufficient 30 draft of air produced to insure complete combustion of the oil such as is not obtained with natural draft burners and which when obtained by a forced draft burner is obtained only through the employment of motor driven apparatus which increases the expense of installation and operation and requires a comparatively skilled operator.

The improvement above referred to is obtained to a less degree by the provision of 35 a cylindrical shell, corresponding to deflector 4, for the elevation of the burner even though it does not provide the maximum amount of draft resulting from the use of the tapered downwardly flaring deflector. With the preferred construction shown 40 it is possible to substantially reduce the flue opening with a damper and also utilize a chimney check draft without producing a smoking blaze in the burner resulting from 45 imperfect combustion. The use of the flue check and damper eliminates wasteful passage of heat up the chimney such as always takes place when it is necessary to leave the flue open to create a draft sufficient to support combustion, and this is necessary with 50 a burner resting on the grate and having the space between the same and the furnace wall blocked off.

It will be noted that the deflector 4 has 55 a circular lower edge while the upper edge is oval in shape so as to be inserted within the flange 20 formed on base 1 and thereby support the burner. Obviously, the draft advantages of my construction would be obtained with the use of a circular burner and 60 the oval contour of the burner and terrace is not essential to this feature of my invention.

65 The deflector may be made in one-piece if it is to be applied to the furnace when the

latter is being installed, or the deflector may be made in sections which may be secured together if it is necessary to insert the sections through the door or other opening in a furnace already in use.

These and other modifications in the construction illustrated may be made without departing from the spirit of my invention as expressed in the following claims.

I claim:

1. In combination, an oil burner, the base of which has a downwardly and outwardly flaring flange, and an air deflector adapted to rest upon a heater grate, the base of which deflector is substantially larger in diameter than said flange and the altitude of which deflector substantially exceeds the altitude of said burner and the upper edge of which fits within said flange and elevates said burner from the heater grate.

2. In an oil burner for insertion in a coal type heater, an oil receiving member, air conduits at the sides of said member extending upwardly, over and downwardly to discharge air over the center of said member, and a downwardly flaring shell adapted to substantially elevate the burner above the heater grate and to form a tapered air passage from the bottom of said heater to said conduits.

3. In combination with a heater having a fire door and a grate substantially spaced from each other vertically, a down draft oil burner located at the level of said fire door and having a cross sectional area much smaller than the sectional area of the firebox of said heater, and a shell converging from the walls of the heater fire box at the level of said grate to the bottom of said burner.

4. In combination with a heater having a fire door and a grate substantially spaced from each other vertically, an oil burner having an oil receiving surface spaced above the bottom of said door and being substantially smaller in area than the cross section of the heater fire-box, an upwardly converging shell extending from the wall of the furnace fire box adjacent said grate to the lower portion of said burner, and air conduits leading from said shell over and downwardly onto the center of said surface.

5. In combination with a heater, having a draft door near its bottom and a grate above such door, a shell forming an air passage converging upwardly from the heater wall at said grate, and a down draft burner at the upper end of said shell supplied with air from said shell.

6. An oil burner comprising an oval upwardly facing member for receiving oil to be vaporized and ignited and for directing the flame of combustion, vertical conduits at the ends only of said oval member, horizontal conduits extending from the upper

ends of said vertical conduits, said conduits providing air passages discharging downwardly onto the central portion of said member.

5 7. In an oil burner of the class described, an oval base, an oil receiving terrace oval in contour and provided with oil retaining grooves arranged in the form of ovals of successively increasing diameters, and air conduits at the ends of the major axis of said base extending upwardly, horizontally over said major axis, and downwardly to discharge over the central part of said burner.

10 8. In an oil burner, an oval base, vertical air conduits at each end of the major axis of said base, and an air deflector leading to said conduits flaring downwardly from the oval contour of said base and having a circular lower edge to fit against the inner wall

20 of a circular stove or furnace.

9. In an oil burner, a base having upstanding collars forming air passages, a conduit telescopingly mounted on said collars to form extensions of said passages and provided with a downwardly directed outlet intermediate said passages, vertical rods extending through said collars and carrying said conduit at spaced points, and adjustable supports for the lower ends of said rods.

30 10. In an oil burner, a base having upstanding collars forming air passages, a conduit telescopingly mounted on said collars to form extensions of said passages and provided with a downwardly directed outlet intermediate said passages, vertical rods extending through said collars and carrying said conduit at spaced points, adjustable supports for the lower ends of said rods, and means for simultaneously adjusting said

40 supports equally.

11. In an oil burner, an oil receiving member, air conduits at the sides of said member extending upwardly, over, and downwardly to discharge air over said member, and a downwardly flaring shell forming a tapered air passage to said conduits, the length of which shell exceeds the height of

said conduits and the diameter of the lower end of which shell substantially exceeds the diameter of its upper end and the diameter 50 of said member.

12. In an oil burner for insertion in a coal type heater, an oil receiving member, air conduits at the sides of said member extending upwardly, horizontally and downwardly to 55 discharge air over the center of said member, and a downwardly flaring shell adapted to substantially elevate the burner above the bottom of the heater and to form a tapered air passage from near the bottom of the 60 heater to said conduits.

13. In an oil burner, an oil receiving member, air conduits at the sides of said member extending upwardly, horizontally, and downwardly to discharge air over the center of 65 said member, and a downwardly flaring shell below said conduits forming a tapered air passage to said conduits, the vertical length of said shell substantially exceeding the vertical height of said conduits and the width 70 of the lower end of said shell substantially exceeding the width of the upper end thereof.

14. In combination with a furnace having a fire door and a draft door substantially spaced from each other vertically, a down draft oil burner with its ignition pan substantially as high as the bottom of said fire door and having an exterior diameter much smaller than the interior diameter of the fire 75 box of the furnace, and a shell member below said burner for receiving air admitted through said draft door and discharging such air to the air conduits of said burner, the height of said shell being at least as 80 great as the radius of said burner and the exterior of said shell being uncovered and exposed to the heat in the fire box of the furnace whereby intaken air is heated before 85 being delivered to the burner. 90

In testimony whereof I hereunto affix my signature this 13th day of February, 1924.

WILLIAM B. PHILIPPE.
